US00D947360S

(12) **United States Design Patent** (10) **Patent No.:** **US D947,360 S**
Cotton et al. (45) **Date of Patent:** **** Mar. 29, 2022**

(54) **MONITOR FOR AN INHALER**

- (71) Applicant: **Vectura Delivery Devices Limited**, Wiltshire (GB)
- (72) Inventors: **Darryl Cotton**, Wiltshire (GB); **Roger Clarke**, Wiltshire (GB); **John Deamer**, Wiltshire (GB); **Andreas Meliniotis**, Wiltshire (GB)
- (73) Assignee: **Vectura Delivery Devices Limited**, Wiltshire (GB)
- (**) Term: **15 Years**

(21) Appl. No.: **29/734,931**

(22) Filed: **May 15, 2020**

(30) **Foreign Application Priority Data**

- Nov. 18, 2019 (EM) 007255740
- (51) **LOC (13) Cl.** **24-02**
- (52) **U.S. Cl.**

(57) **CLAIM**

The ornamental design for a monitor for an inhaler, as shown and described.

DESCRIPTION

FIG. 1 is a perspective view of a monitor for an inhaler from above and one side.

FIG. 2 is a perspective view of the device from below and other side.

FIG. 3 is a front view of the device.

FIG. 4 is a rear view of the device.

FIG. 5 is a side view of the device.

FIG. 6 is the other side view of the device.

FIG. 7 is a top plan view of the device; and,

FIG. 8 is a bottom plan view of the device.

The broken lines in the drawings show portions of the monitor for an inhaler that form no part of the claimed design.

1 Claim, 8 Drawing Sheets
